[57] CLAIM

The ornamental design for a drafting parallel, as shown and described.

DESCRIPTION

FIG. 1 is a top plan view of a drafting parallel showing my new design, an intermediate portion being broken away to indicate intermediate length;

FIG. 2 is a bottom plan view thereof;

FIG. 3 is the side elevational view thereof;

FIG. 4 is the end elevational view thereof; and

FIG. 5 is a cross-sectional view taken along line 5—5 of FIG. 3.
